(57) CLAIM

(22) Filed: Feb. 3, 2012

The ornamental design for a champagne bottle cork cage ornament, as shown and described.

(51) LOC (9) CL. 11-02

DESCRIPTION

(52) U.S. CL. D11/157

FIG. 1 is a perspective view of a champagne bottle cork cage ornament showing my new design;

(58) Field of Classification Search D11/130,

FIG. 2 is a front elevation view thereof;

D11/157, 184, 164; D7/560, 564, 563, 571,

FIG. 3 is a back elevation view thereof;

D7/628, 604, 606, 625, 601; D9/681, 600;

FIG. 4 is a left side elevation view thereof;

D3/270, 271.1; 206/457

FIG. 5 is a right side elevation view thereof;

See application file for complete search history.

FIG. 6 is a top view thereof; and,

FIG. 7 is a bottom view thereof.

The broken line showing of the text on the wine bottle label forms no part of the claimed design.
